SERIES FLUX VIBRATOR FOR USE ON
SYNCHRONOUS CLOCK MOTORSEdgar A. Phaneuf, Southborough, Mass., assignor
to Telechron, Inc., a corporation of Maine

Application February 26, 1948, Serial No. 10,993

4 Claims. (Cl. 58—38)

1

My invention relates to alternating current motor vibrators such as are employed on synchronous motor-operated alarm clocks, and its object is to provide an improved vibrator arrangement which utilizes the entire series flux of the motor for its operation and, hence, is capable of developing a greatly increased amount of vibrating energy for a given size of motor as compared to shunt flux-operated vibrators such as, for example, are described in United States Patent No. 2,002,433 to Cowles, May 21, 1935. The vibrator of my invention is in series with the entire motor flux circuit of the motor and is readily adapted for application to various types of motors, including the concentric core type such as is described in United States Patent No. 1,977,186 to Haydon, October 16, 1934, as well as to motor structures such as are described in the above-mentioned Cowles patent. Moreover, instead of shunting flux away from the motor air gap and therefore decreasing the flux available for motor torque, I have found that my magnetic vibrator which is in series with the motor flux and rotor air gap distinctly improves the motor torque of reluctance-type motors when the vibrator is in operation.

The features of my invention which are believed to be novel and patentable will be pointed out in the claims appended hereto. For a better understanding of my invention, reference is made in the following description to the accompanying drawing in which Fig. 1 shows in part a front elevation and Fig. 2 in part a bottom view of an alternating current clock motor structure to which my invention has been applied, by providing an air gap in the stator magnetic circuit at one end of the core and resiliently mounting the core so that this gap will open and close with the flux pulsations. Fig. 2 also shows cam means for holding the gap closed when a vibratory alarm noise is undesired, and time control release means for causing the vibratory alarm to sound at a selected time. Fig. 3 shows in part a rear elevation and Fig. 4 a plan view of a concentric core type of alternating current clock motor and the application of my invention thereto for alarm clock purposes; and Fig. 5 shows in part an end elevation and Fig. 6 in part a bottom view of an alternating current motor of the multipolar offset core type representing the application of my invention thereto.

In Figs. 1 and 2 there is represented a two-pole, shaded-pole synchronous motor of the type described in United States Patent No. 1,768,386 to Warren, June 24, 1930, to which my invention

has been applied. The stator comprises the laminated magnetic core 1 about which the single phase exciting coil 2 is wound and the two laminated pole piece limbs 3 and 4. Adjacent the rotor air gap these limbs are split into two halves and have shading coils 5 on each trailing pole half. A polar rotor 6 of the hysteresis type is mounted for rotation within the rotor air gap and is schematically represented for driving an alarm clock gear train 7 having an alarm cam 8 which will be driven at one revolution in twelve or twenty-four hours and is adjustable relative to the clock hands for setting the time for the alarm to sound. As represented in Fig. 2, the cam 8 may be connected to its driving gear by a friction clutch 9, so as to be adjusted with respect to such gear by the thumbpiece 10 on the shaft of cam 8.

As shown in Fig. 2, I have provided an adjustable air gap 10 between the limb 4 and core 1 of the motor stator in series with the flux circuit of the motor. The stator structure is supported by posts 23 at its rotor end, and the core 1 is sufficiently resiliently mounted so that it may vibrate between the open gap position represented in Fig. 2 to a position in contact with limb 4. The normal position when unrestrained and with the motor unexcited is that shown. When the motor is excited with commercial frequency alternating current, the flux crosses this gap and magnetic attraction causes the parts to be drawn together and the gap closed synchronously with the flux pulsations, and to open again as the flux passes through zero values. Thus the magnetic parts which face each other across this gap vibrate and cause a vibrating noise as they strike together. The resiliency of the mounting must be such as to permit this if the vibratory alarm noise is to be obtained, and the loudness of this noise depends somewhat upon the maximum air gap which occurs at 10 and the resiliency of the mounting. As represented in Fig. 2, the end of core 1 adjacent gap 10 is supported by a nonmagnetic spring arm 11 secured to limb 4 by a bolt or rivet 12. The other end of core 1 is preferably fastened rigidly to the otherwise free end of limb 3. When so mounted, the core vibrates sufficiently for the intended purpose. I have tried mounting both ends of the core resiliently as described for the one end. While this increases the vibratory noise, it is unnecessary as the one gap is sufficient for this purpose.

In Fig. 2 there is shown a cam 13 the periphery of which forms a back stop for the vibratory end 55 of core 1. The position of this cam represented

in Fig. 2 allows a maximum air gap at 10. Rotating the cam 13, 180 degrees from the position shown, closes the gap 10 and prevents the vibration described even though the motor be energized. Hence, the rotary position of this cam and its shape determine the absence or presence of the vibratory alarm and its loudness when vibration is permitted, and serve as a device for turning on and off the alarm when the motor-driven clock is in operation.

It is now a simple matter to associate this cam with the usual alarm letoff device found on alarm clocks, so as to cause the vibratory alarm to sound at a predetermined set time, and also to shut the alarm off manually when the sleeper has been awakened. One way of doing this is somewhat schematically illustrated in Fig. 2. Associated with the periphery of the alarm cam 8 is a cam follower lever 14 pivoted at 15 and biased by gravity, or otherwise, to rest against the cam 8. This lever has two offset latches 16 and 17 thereon. The shaft of cam 13 has a thumb-piece 18 for turning it manually. It also has a latch arm 19 having an offset latch projection at 20. In the alarm on position of cam 13 shown, the arm 19 rests against a stop 21 and is biased counterclockwise against this stop by a spring 22. To shut the alarm off, cam 13 and arm 19 are rotated about 180 degrees more or less clockwise manually where the latch projection 20 on the arm cooperates with either latch 16 or 17. These latches are beveled so that when arm 20 is turned manually to the off position, the latch projection will pass by behind whichever latch 16 or 17 it engages and, in so doing, the cam lever will be momentarily moved to the left, lifting its cam follower off cam 8 and dropping back again as soon as the engaging latch has been passed by. The latches 16 and 17 are slightly staggered so that if the cam follower end of lever 14 is in the depression of the alarm cam 8, latch 20 will engage with latch 17; and when the arm 19 has been turned clockwise slightly beyond the position of latch 17 and released, the latch 17 will hold arm 19 in this alarm off position.

If, on the other hand, lever 14 rests on the high part of cam 8 when the alarm is turned off, latch finger 20 will contact latch finger 16 and will not contact latch finger 17 even though turned that far. When released, arm 20 will be held by latch 17 in alarm off position. When the lever 14 again drops into the depression in alarm cam 8, arm 20 will be released and spring 22 will move it to the alarm position shown and the alarm will sound. In case the alarm is turned off very soon after it sounds automatically and arm 19 is retained by latch 17 as above described, when the lever 14 is shifted to the left by the rise in the cam 8, lever 19 will be released by latch 17 but will then be caught by latch 16. Hence, this double staggered latch arrangement is advantageous in that the alarm may be turned off immediately and will reset itself automatically for the next scheduled automatic alarm operation without further attention. In the usual alarm clock, if the alarm is turned off immediately after it sounds, it must be reset for automatic operation some time later. Otherwise, it will not operate at the next scheduled alarm period.

It is to be noted that except for the relatively short proportion of the time when the alarm is in vibratory operation, assuming normal conditions, the gap 10 is closed and the motor magnetic circuit has a reluctance corresponding to that of a normal motor and hence has starting

and operating characteristics corresponding to a normal motor. No flux is shunted from the rotor flux path. When the alarm is in operation, it can produce the maximum noise energy possible for a given watt input to the motor. The running characteristics of the hysteresis type of motor described do not appear to be affected when the vibrator is in operation, and the starting characteristics of this type of motor appear to be only slightly impaired.

Figs. 3 and 4 represent the application of the invention to the concentric coil type of synchronous reluctance motor, or a motor of the type described in United States Patent No. 1,977,186. In this type of motor a central magnetic core 24 is surrounded by an energizing coil 25. To one end of the core is fastened a polar magnetic plate 26, and closely adjacent thereto and concentric with the core is a polar magnetic rotor 27. The magnetic circuit from the other end of the core is completed by a magnetic cup 28, which in the usual motor of this type has its inner bottom centered against the end of the core opposite or otherwise magnetically connected thereto. The side walls of the cup 28 extend adjacent the rotor periphery and in some cases may have polar teeth cut therein opposite the rotor.

I have modified this construction by providing an opening in the bottom of the cup 28 so that it is spaced from the core by a nonmagnetic spacer washer 29 such that there is the equivalent of a concentric air gap at this point. Then I provide a washer-shaped magnetic part 30 resiliently mounted adjacent the magnetic gap at 29 and large enough to bridge the concentric gap between the core and magnetic part 28. The resilient mounting of part 30 is such that it is normally spaced slightly away from the core 24 as shown but such as to be magnetically attracted to strike against the adjacent magnetic parts in synchronism with the alternating flux pulsations in the magnetic circuit of the motor to produce a vibratory alarm when the motor is energized with alternating current. In the example shown this resilient mounting comprises a nonmagnetic resilient strap 31 secured between the side wall of the cup 28 and the magnetic armature member 30 of the vibrator. It is thus seen that the vibrator is operated by the series flux of the motor.

In order to prevent this vibrator alarm from operating, the armature 30 may be held from vibration either in the position shown or up against the end surfaces of core 24 and cup 28, and for this purpose I have shown a bail type of spring wire clamp such as is commonly used on fruit jars to hold the armature up against the core. This clamp consists of wire having a clamping part 32 diametrically embracing the central part of the armature 30 and retained in such central position by a slotted guide part 33 fixed to the armature, and a bail-like operating lever part 34 for moving the part 32 between clamping and unclamping positions. The lever part 34 is pivoted to opposite sides of the motor shell 28 and secured to clamping part 32 on a line sufficiently offset from the pivot axis so as to obtain a lever action on the part 32 to move it between armature clamping and unclamping positions. The parts as shown in Fig. 4 are in the unclamped position. Armature 30 is biased to the detracted position by spring 31 and is free to vibrate. The slot in guide 33 permits such vibration without interference from clamping wire member 32. When the lever part 34 is pulled down to the

dotted line position indicated 34a, the clamping part 32 is pulled down securely to clamp the armature 30 against the end of the motor housing in nonvibrating flux gap closing position.

When the part 34 is thus moved from full line position to position 34a, there is a resilient tensioning of the wire parts so that, if released, it will spring back to full line position. If the part 34 be moved still further to the position indicated by dotted lines at 34b, it will be retained in this position by reason of a toggle action of the wire parts. In this 34b position the armature is also clamped in nonvibrating flux gap closing position.

In Fig. 4, I have indicated a gear reduction train 33 by means of which the motor shaft 36 may drive hour and minute clock hands 37 and 38. Geared to the hour hand shaft is an alarm cam member 39. A friction clutch 40 intervenes to enable the cam to be set by an alarm setting shaft 41. I have shown an alarm release lever 42 pivoted at 43 and arranged to be released by the cam pin 39 as such pin is rotated past one position in its path of rotation. Lever 42 is provided with a latch at 44, movable into and out of a position to hold or release wire lever 34 when in the alarm set position 34a. The lever 42 may be biased to such holding position against a stop as by a spring 45. It is now evident that if lever 34 be in position 34a and retained there by the release lever 42, and the clock is in operation, a time will arrive when pin 39 moving down and to the right as seen in Fig. 4 will engage the free end of lever 42 and move it to the right and thus release the alarm at a time determined by the alarm setting. The series motor flux vibrator armature 30 will then sound a vibratory alarm until shut off by moving lever 34 to position 34a or 34b. The alarm may be permanently shut off immediately after it starts to operate by moving the lever 34 to position 34b. Later when the release lever 42 has moved back to holding position, lever 34 may be moved manually from position 34b to 34a to set the alarm for the next scheduled alarm period.

I have found that with respect to the reluctance type of synchronous motor here briefly described, the starting and operating characteristics are actually substantially improved when the vibrator alarm is in operation. Apparently the synchronous opening and closing of the flux gap by the vibrating armature 30 has a beneficial effect in controlling the size or shape of the flux pulsations which act upon the polar motor rotor 27. When the armature of the vibrator is held in nonvibrating, gap closing position, the motor operation characteristics are those of the normal motor of this type. The series flux vibrator alarm is especially beneficial for use with motors of the type shown in Figs. 3, 4, because with these types of motors it is not practicable to use a shunt flux vibrator.

In Figs. 5 and 6 my invention is shown as applied to the offset type of multipolar single phase synchronous motor. In this type of motor there is a magnetic core 46 surrounded by a single phase coil 47. From opposite ends of the core magnetic stator plates 4 and 48 extend at right angles to the core in one direction. The extremities of these plates each have a circular series of teeth or pole pieces 50 offset toward each other and interleaved so as to form a partial circle of uniformly spaced teeth of opposite polarity. This general type of motor is described in my patent No. 2,541,830, February 13, 1951. Within this

partial circle is a polar rotor 52 rotatively supported on an axis of rotation at 51. Supporting studs 53 of the pillar type space and secure the plates. The construction of the motor of Figs. 5 and 6 is conventional except that one of the side plates 49 is not secured to the core 46 but has an opening 54 somewhat larger than a reduced end section 55 of the core, which reduced core section extends through such opening 54 with sufficient clearance so that these parts do not contact each other. Also, the plate 49 is normally spaced slightly from the adjacent end of the larger section of the core so as to leave an air gap at 56. The stator plate 48 at the opposite end is rigidly secured to the core and to stationary supporting structure designated at 57, and the plate 49 which forms the vibrator armature of the alarm is secured to plate 48 by the studs 53. Thus the lower end of plate 49 as represented in Fig. 5 is unsupported and there is sufficient resiliency in this plate and in its supporting structure to allow the lower end to vibrate as a magnetic armature when the motor is energized by single phase alternating current and, in so doing, to move to and from the position represented in Fig. 6 and strike against the end of large core part 46.

This series flux vibrator arrangement in no way interferes with the operation of the motor and, in fact, improves its starting and operating characteristics when the armature is allowed to vibrate and at the same time is operating as a sound vibrator. When the vibrator sound is not desired, I provide a shutoff device consisting of a cam lever 56 pivoted at 57 to the reduced core extension 55. The position of this cam lever represented in Fig. 6 allows the armature plate 49 to vibrate, and the loudness of the sound produced may be controlled by an adjustable back stop 58 for such lever. The lever is biased against the stop 58 by a spring 59.

When the vibrator alarm is to be shut off, lever 56 is pulled over to the right and retained by a catch 60 and a pin 61. This presses the armature plate 49 against the end of large core part 46 and closes the gap 56. The latch 60 may be released manually or in response to an alarm clock release mechanism as previously explained and when released, allows the cam lever 56 to be pulled over to the alarm on position represented by spring 59.

What I claim as new and desire to secure by Letters Patent of the United States is:

1. In combination, a single phase alternating current motor having a magnetic circuit energized by a single phase winding, a rotor for said motor and a magnetic vibrator in series in the flux path of said magnetic circuit, said magnetic vibrator comprising relatively movable magnetic parts resiliently biased in spaced relation to provide a magnetic gap in series in the flux path of the motor, which parts are adapted to be alternately magnetically attracted together and separated by the resilient bias in vibratory synchronous relation with the flux pulsations of said motor, and means movable between releasing and holding positions for holding the parts of said vibrator together when said means is in holding position.

2. In combination, a single phase alternating current motor having a magnetic circuit energized by a single phase winding, a rotor for said motor and a magnetic vibrator in series in the flux path of said magnetic circuit, said magnetic vibrator comprising relatively movable magnetic parts resiliently biased in spaced relation to provide a magnetic gap in the series flux path of

the motor, which parts are adapted to be alternately magnetically attracted together and separated by the resilient bias in vibratory synchronous relation with the flux pulsations of said motor, and means movable between releasing and holding positions for holding the parts of said vibrator against vibration when said means is in holding position.

3. In combination, a single phase alternating current motor comprising a magnetic circuit, a single phase winding for energizing said magnetic circuit, a rotor for said motor and a magnetic vibrator in series at different points in said magnetic circuit, said magnetic vibrator comprising relatively movable magnetic parts, one of which is resiliently biased in spaced relation to the other part to provide a magnetic gap in series in the flux path of said motor, which parts are adapted to be alternately magnetically attracted together and separated by the resilient bias in vibratory synchronous relation with the flux pulsations of said motor, control means movable between releasing and holding positions for holding said parts against vibration when said control means is in holding position, means for biasing said control means toward the releasing position, and means for releasably holding said control means in holding position.

4. In combination, a single phase alternating

current synchronous motor, said motor having a magnetic circuit, a single phase coil for energizing said circuit, and a motor rotor and a magnetic vibrator in series in the flux path of said magnetic circuit, a control means associated with said magnetic vibrator movable between holding and releasing positions for holding said magnetic vibrator against vibration when said control means is in holding position, means for biasing said control means toward releasing position, a releasable catch for holding said control means in holding position, and means responsive to the operation of said motor for releasing said catch at a predetermined time.
